UNITED STATES PATENT OFFICE.

JOHN L. GRAHAM, OF REYNOLDSVILLE, PENNSYLVANIA, ASSIGNOR TO WICKES BROTHERS, OF SAGINAW, MICHIGAN, A CORPORATION OF MICHIGAN.

OSCILLATION FOR GANG-SAWS.

968,342.

Specification of Letters Patent. Patented Aug. 23, 1910.

Application filed March 26, 1908. Serial No. 423,484.

To all whom it may concern:

Be it known that I, JOHN L. GRAHAM, a citizen of the United States, residing at Reynoldsville, in the county of Jefferson 5 and State of Pennsylvania, have invented certain new and useful Improvements in Oscillation for Gang-Saws; and I do hereby declare the following to be a full, clear, and exact description of the invention, such as 10 will enable others skilled in the art to which it appertains to make and use the same.

This invention relates to means for shifting the positions of the arcs of oscillation of slides for gang saws, and consequently the 15 incline of the slides.

One object is the provision of means for maintaining a proper relation between the amount of forward advance of the saws and the rate of feed of timber to the saws.

20 Another object is the provision of means for automatically shifting the positions of the arcs of movement of the slides simultaneously with the adjustment of the rate of feed of the timber.

25 To these ends, therefore, my invention consists in certain novel features and combinations, such as will be more fully described hereinafter and particularly pointed out in the claims.

30 In the accompanying drawings, Figure 1 is a side view of my invention applied to a gang saw; Fig. 2 is an end view of a gang saw; Fig. 3 is a detail cross-sectional view showing an adjustable shaft connection and 35 the means for effecting its adjustment and Fig. 4 is a sectional side view illustrating the slides in which the saw sash is received and their connection with the shafts.

(A) indicates a gang saw frame, to the 40 inner faces of which are pivoted the slides arranged in pairs (1) (1) and (2) (2) and pivotally supported as at *c*, *c*. These slides are adapted to receive blocks *d*, *d*, in which the horn pins 8, 8, carried by the sash 7, are 45 received, and it will be observed that the pivotal points of the slides are in approximately the same horizontal plane with the horn pins when the latter are at their upper limits of movement as shown in Fig. 4. 50 Rock shafts (3) and (4) are journaled on the frame, the shafts each carrying an arm (5) suitably connected to the free ends of the slides in any convenient manner as by

the rods *e*, *e*. A linkage (6) connects the two rock shafts, whereby motion imparted 55 to one will be transmitted to the other.

Generic claims to the invention herein disclosed are contained in my co-pending application filed March 26, 1908, Serial No. 423,486. 60

The rock shafts are oscillated for the purpose of swinging the slides toward and from the constantly-infeeding timber whereby the saws are advanced toward the timber in proportion to the speed of travel of the 65 saws and the rate of feed of timber thereto.

It is often desirable to increase or diminish the rate of feed of the timber to the saws and in such instances it is necessary, in order that the saw make a full cut and that 70 each tooth engaging the timber may cut an equal or substantially equal length of chip, that the position of the arc of oscillation of the slides and hence the incline of the slides be changed, (the amount of oscillation remaining constant), whenever the rate of feed of the timber is adjusted. To this end, I provide the following mechanism as one exemplification of my invention. The rock shaft (4) is provided with a crank (9). A 80 countershaft (10) is journaled to the front of the gang frame and is provided with a similar crank (11) connected to crank (9) by means of a couple of preferably alined rods (12) (12), the adjacent ends of which 85 are connected by means of a turn-buckle (13). The countershaft (10) is oscillated by means of a crank arm (14) and link (15), the latter eccentrically connected to the main drive shaft (16). The counter-shaft (10) has a fixed arc of oscillation, but 90 a rotation of the turn-buckle (13) will shorten or lengthen the combined length of rods (12) to partially rotate the shaft (4) in one direction or the other and thereby 95 vary the position of the arc of oscillation of the slides (1) (1) (2) (2), and consequently the incline of the slides relative to a fixed vertical line.

A number of means may be employed to 100 rotate the turn-buckle in one direction or the other either manually or automatically and as one method for obtaining an adjustment of the rock shaft (4) simultaneously with the adjustment of the rate of feed, I 105 may provide the following construction.

The feed works comprise feed rolls (17) journaled in the frame of the gang, the feed rolls being driven by the gears (18) (18) actuated from the bevel gear (19) with which pinion (20) meshes. The pinion (20) is fast on a shaft (21). A friction-wheel (22) is slidably mounted on the shaft (21) and engages the friction drive disk (23). In order to shift the friction-wheel relative to the disk (23), I provide a sliding rod (24) controlled by a hand-wheel (25). The rod carries an arm (26) connected to the hub of the friction wheel (22). Movement of the rod will therefore, shift the friction-wheel relative to its disk to vary the speed of rotation of the rolls (17) and consequently the feed. To simultaneously shift the positions of the arcs of movement of the slides, I provide the sliding rod (24) with a second arm (27), its outer end being secured to a rack (28) adapted to mesh with the teeth of a gear (29) feathered as at (30) on the turn-buckle (13). Movement of the sliding rod in one direction or the other will raise or lower the rack, rotating the gear (29) and turn buckle 13 in one direction or the other to lengthen or shorten the connection between the rock and counter shafts (4) and (10) to swing the rock shaft and change the position of the arcs of movement of the slides.

Having thus fully disclosed my invention, what I claim as new is—

1. As a means for adjusting the amount of advance of a saw gang toward the cant, the combination with a sash, horn pins carried thereby, a plurality of pairs of slides, means for pivotally supporting the slides on a plane approximately horizontally in line with the horn pins when the latter are at their upper limits of movement, a main rock shaft, a linkage connecting the shaft with at least one pair of slides, a countershaft independent of the linkage, and lying substantially parallel with the rock shaft, means for imparting a fixed oscillation thereto, and adjustable means connecting the counter-shaft and the main rock shaft for varying the position only of the arc of movement imparted to the slides.

2. As a means for adjusting the amount of advance of a saw gang toward the cant, the combination with a sash, horn pins carried thereby, a plurality of pairs of slides, means for pivotally supporting the slides on a plane approximately horizontally in line with the horn pins when the latter are at their upper limits of movement, a main rock shaft, a linkage connecting the shaft with at least one pair of slides, a counter-shaft spaced apart from and substantially parallel with the rock shaft, the counter-shaft being independent of the linkage, means for imparting a fixed oscillation to the counter-shaft and rock shaft respectively, and a longitudinally adjustable rod connecting the arms.

3. As a means for adjusting the amount of advance of a saw gang toward the cant, the combination with a sash, horn pins carried thereby, a plurality of pairs of slides, means for pivotally supporting the slides on a plane approximately horizontally in line with the horn pins when the latter are at their upper limits of movement, a main rock shaft, a linkage connecting the shaft with at least one pair of slides, a counter-shaft spaced apart from and substantially parallel with the rock shaft, the counter-shaft being independent of the linkage, means for imparting a fixed oscillation to the counter-shaft, arms carried by the counter-shaft and rock shaft respectively, a rod pivotally secured to each arm, a turn buckle connecting the adjacent ends of the rods, and means for actuating the turn buckle to adjust the connection during the operation of the machine.

4. As a means for adjusting the amount of advance of a saw gang toward the cant, the combination with a sash, horn pins carried thereby, a plurality of pairs of slides, means for pivotally supporting the slides on a plane approximately horizontally in line with the horn pins when the latter are at their upper limits of movement, a main rock shaft, a linkage connecting the shaft with at least one pair of slides, a counter-shaft spaced apart from and substantially parallel with the rock-shaft, the counter-shaft being independent of the linkage, means for imparting a fixed oscillation to the counter-shaft, arms carried by the counter-shaft and rock shaft respectively, a rod pivotally secured to each arm, a turn buckle connecting the adjacent ends of the rods, a gear feathered on the turn buckle, and means for rotating the gear to vary the position of the arc of movement of the gang, the length of such arc remaining constant.

5. In a gang saw, a sash, horn pins carried thereby, a plurality of pairs of slides, means for pivotally supporting the slides on a plane approximately horizontally in line with the horn pins when the latter are at their upper limits of movement, a rock shaft, a linkage connecting at least one pair of slides and the rock shaft, a counter-shaft lying substantially parallel with the rock shaft and independent of the linkage, means for imparting a fixed oscillation to the rock shaft, an adjustable connection between the counter-shaft and rock shaft for varying the positions only of the arcs of movement imparted to the slides, a feed mechanism, means for changing the rate of feed, and means connecting the means controlling the rate of feed and the adjustable connection to the end that the adjustment of the rate of feed will simultaneously adjust the po-

sition of the arc of movement imparted to the slides, the length of such arc remaining constant.

6. In a gang saw, a sash, horn pins carried thereby, a plurality of pairs of slides, means for pivotally supporting the slides on a plane approximately horizontally in line with the horn pins when the latter are at their upper limits of movement, a rock shaft, a linkage connecting at least one pair of slides and the rock shaft, a counter-shaft lying substantially parallel with the rock shaft and independent of the linkage, means for imparting a fixed oscillation to the rock shaft, arms carried by the crank shaft and the rock shaft, rods pivotally connected to the arms, a turn buckle connecting the adjacent ends of the arms, a gear feathered on the turn buckle to permit longitudinal movement of the latter, and means for rotating the gear.

7. In a gang saw, the combination with a plurality of pairs of slides, of a rock shaft, a linkage connecting the shaft with at least one pair of slides, a power shaft, a counter-shaft having a fixed arc of oscillation imparted thereto from the power shaft, an adjustable connection between the counter-

shaft and the rock shaft for actuating the latter, to shift the position of the arc of movement imparted to the slides, the length of such arc remaining constant irrespective of its position, and means for adjusting such connection to shift the position of the arc of movement of the slides while the machine is in motion.

8. In a gang saw, the combination with a pair of pivotally-mounted slides, a rock shaft, and a linkage connecting at least one of the slides to the rock shaft, a counter-shaft, means for imparting a fixed oscillation to the counter-shaft, arms fastened to the rock- and counter-shafts respectively, a rod pivotally secured to each arm, a turn-buckle connecting the adjacent ends of the rods, a gear feathered on the turn-buckle, a feed works, a rod for changing the rate of feed, an arm carried by the rod, and a rack secured to the arm and in mesh with the gear.

In testimony whereof, I affix my signature in presence of two witnesses.

JOHN L. GRAHAM.
